CLOTHESPIN

Newell H. Curtis, Montpelier, Vt., assignor to Vermont Plastics, Inc., Montpelier, Vt., a corporation of Vermont

Application January 13, 1948, Serial No. 1,961

2 Claims. (Cl. 24—84)

1

This invention relates to new and useful improvements in clothes pins and the primary object of the present invention is to provide a clothes pin including novel and improved means for hanging the clothes pin from a structural element such as a line or the like in a conveniently accessible position.

Another important object of the present invention is to provide a clothes pin including a pair of companion arms having opposed pockets facilitating the positive clamping engagement of the present clothes pin with an article of clothing.

A further object of the present invention is to provide a clothes pin of plastic material facilitating the same to be used outdoors for long periods of time without affecting the normal efficiency of the device for clamping supporting elements of clothing.

A still further aim of the present invention is to provide a clothes pin of the aforementioned character that is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the present invention hanging from a line (shown in section);

Figure 2 is a front elevational view corresponding with Figure 1.

Figure 3 is a longitudinal vertical sectional view taken substantially on the plane of section line 3—3 of Figure 2.

Figure 4 is a longitudinal vertical sectional line taken substantially on the plane of section line 4—4 of Figure 1.

Referring now to the drawings in detail, wherein for the purpose of illustration, there is disclosed a preferred embodiment of the present invention, the numerals 10 and 12 represent a pair of companion arms of preferably plastic material generally each comprising a flat outer face 14, a pair of spaced parallel side walls 16 and 18 having straight edges 20 at one end that incline inwardly as at 22 toward the rear terminals 24 of the arms 10 and 12.

Projecting inwardly from the forward ends of the arms 10 and 12 and integrally formed with

2

the arms 10 and 12 are opposed gripping jaws 28 having inclined tips 30 and opposed notches 32. The bearing portions 34 of these jaws 28 terminate in a plane parallel with the straight edges 20 of the side walls 16 and 18.

Integrally formed with the arms 10 and 12 at substantially the centers of said arms are projections or lugs 36 having concaved pockets or recesses 38 that frictionally engage a coil spring 40. The end portions or arms 42 and 44 of this spring extend along opposite sides of the arms 10 and 12 and are provided with angulated extremities 46 and 48 that frictionally engage notches 50 and 52 provided in the outer faces of the arms 10 and 12 adjacent the forward ends 26 of the arms 10 and 12. Said spring 40 normally retains the jaws 28 in a clamped position as shown best in Figures 1 and 3 of the drawings.

The numeral 54 represents the hanger element 20 used in conjunction with the present invention generally comprising a preferably flat strip of metal having a hook 56 at the one end that terminates in an inclined tip 58 that prevents disengagement of the hook 56 with a supporting line 60. The opposite end 62 of the hanger element 54 is provided with notches 64 in opposite edges that engage a pair of adjacent loops or coils of the spring 40. Obviously, the hanger may be quickly and readily disengaged from the spring 40 by 30 merely twisting the hanger so that the same may be slid from its position between the coil spring.

It should be noted, that the ends 24 of the arms 10 and 12 and the outer extremities of the tips 30 are rounded as at 66 to prevent tearing of garments gripped between jaws 28. Also, it is noted that opposed pockets or recesses 68 between lugs 36 and jaws 28 are provided to facilitate a tight gripping action of the jaws.

Having described the invention, what is claimed 40 as new is:

1. A plastic clothes pin comprising a pair of opposed arms each having flat outer faces and spaced side walls, opposing gripping jaws at one end of said arms, opposed recesses provided in said arms intermediate the ends of said arms, a coil spring positioned in said recesses, said spring having outwardly projecting arm portions bearing against opposite side walls of said arms, said arm portions of said spring having angulated extremities, transverse seats provided in the outer faces of said arms adjacent said gripping jaws receiving the angulated extremities of said arm portions, a hanger having a hook portion at one end, notches provided in the other end of said hanger 50 engaged between a pair of adjacent coils of said

spring, and gripping pockets provided in the inner faces of said arms adjacent said jaws.

2. A clothes pin comprising a pair of arms having companion gripping jaws, means normally retaining the jaws in clamped position, said means including a coil spring positioned between said jaws, an elongated hanger arm having notches at one end receiving a pair of adjacent convolutions of said spring, a hook at the free end of said hanger arm, and a pair of opposed gripping pockets 10 provided in the inner faces of said arms adjacent said jaws.
